UNITED STATES PATENT OFFICE

2,637,135

CURTAIN STRETCHER

Walter Karas, Detroit, Mich.

Application April 4, 1952, Serial No. 280,589

8 Claims. (Cl. 45—24)

1

This invention relates to curtain stretchers, and more particularly, has reference to a knock-down curtain stretcher adjustable as to length and width and adapted, in any position of adjustment, to expose a rectangular pattern of nails for engaging the edge of a curtain to be stretched.

It is old in the art to provide a curtain stretcher having longitudinal and transverse frame members each of which comprises telescopically related frame portions, and no claim is made to this arrangement per se. However, it is desirable that a curtain stretcher have, at all times, a rectangular series of sharply pointed, closely spaced nails extending laterally from the frame, and the provision of such a series in a curtain stretcher of the telescopic type presents difficulties, since the nails would ordinarily interfere with the making of the necessary telescopic adjustments.

It has heretofore been proposed that a curtain stretcher be provided with retractable means for engaging a curtain to be stretched, but to my knowledge there has not been previously devised an arrangement wherein the act of adjusting associated frame portions telescopically relative to one another will be effective to cause the retraction or extension of the curtain-engaging nails.

It is an important object of the present invention to provide a curtain stretcher wherein the telescopic adjustment of the component parts thereof will be effective to provide the desirable result stated above.

Another important object is to provide a curtain stretcher as stated wherein retraction and extension of the curtain-engaging nails or pins will be accomplished by a concealed series of cams, that are actuated by telescopic adjustment of associated frame portions relative to one another.

Still another important object is to provide a curtain stretcher as stated wherein, in any position of relative telescopic adjustment of the parts, the rectangular series of pins will be unbroken throughout the periphery of the curtain stretcher, with the nails or pins of said series being disposed in a common plane, thus to hold the curtain engaged thereby in a completely flat position and assure the uniform stretching thereof.

A still further important object of the invention is to provide a curtain stretcher as described which, though of telescopic construction and though provided with a means for effecting the retraction and extension of the curtain-engaging nails responsive to the making of the desired

telescopic adjustments, will nevertheless be of knock-down construction, thus to be capable of being stored in a relatively small area.

Summarized briefly, the invention comprises a rectangular frame composed of a pair of parallel longitudinal members and parallel transverse members extending between and connected to said longitudinal members. Each member of the frame comprises telescopically related frame portions, one frame portion of each member being provided with a longitudinal series of nails fixedly mounted thereon. The other frame portion of each member telescopes within the frame portion having the fixed nails, and is provided with a longitudinal series of retractable nails. Pivottally mounted within the frame portion having the retractable nails is a longitudinal series of cams operatively associated with said nails in a manner to cause the retraction or extension thereof, and mounted in the frame portion having the fixed nails is a cam-engaging means which is effective to engage the cams in succession on telescoping of the frame portions, thus to cause the retraction of a predetermined number of the movable nails responsive to the telescoping of one frame portion into the other.

Other objects will appear from the following description, the claims appended thereto, and from the annexed drawing, in which like reference characters designate like parts throughout the several views, and wherein:

Figure 1 is a front elevational view of a curtain stretcher formed in accordance with the present invention;

Figure 2 is an end elevational view, taken from the left of Figure 1;

Figure 3 is a fragmentary, exploded perspective view of one corner of the curtain stretcher;

Figure 4 is an enlarged, transverse sectional view taken on line 4—4 of Figure 1;

Figure 5 is a sectional view taken on line 5—5 of Figure 4;

Figure 6 is a sectional view taken on line 6—6 of Figure 5;

Figure 7 is a sectional view taken on line 7—7 of Figure 5; and

Figure 8 is a fragmentary, exploded perspective view of the telescoping parts of associated frame portions.

Referring to the drawings in detail, the reference numeral 10 designates one frame portion of one of the longitudinal frame members of the curtain stretcher. Said frame portion may be conveniently termed the outer frame portion of the frame member of which it is a part, since

it receives telescopically the other frame portion of the same longitudinal frame member.

The reference numeral 12 designates generally the outer frame portion of the other longitudinal frame member of the curtain stretcher, the reference numerals 14 and 16 designating generally the outer frame portions of the respective transverse frame members of the stretcher.

Telescoping within the outer frame portion 10 is an inner frame portion 18, and telescoping within the outer frame portion 12 is an inner frame portion 20. An inner frame portion 22 telescopes within the outer frame portion 14 of one transverse frame member of the curtain stretcher, with an inner frame portion 24 telescoping within the outer frame portion 16 of the other transverse frame member.

By reason of the construction so far illustrated and described, it is seen that the curtain stretcher includes a rectangular frame comprising a pair of parallel longitudinal frame members and a pair of parallel transverse frame members, each frame member of the stretcher being formed of telescopically related frame portions which, as shown in Figure 8, are of tubular construction.

The construction of the several outer frame portion 10, 14, 12, and 16 is basically the same, said outer frame portions differing from one another only as to length and as to the means for connecting the same to adjacent frame portions at the several corners of the curtain stretcher frame. Thus, the outer frame portions 14 and 16 are of identical, though opposite construction, and the outer frame portions 10 and 12 are also of identical, though opposite construction. Therefore, as will be apparent hereinafter, a description of one will suffice for all, and the outer frame portion 14 only will be described so far as the details of its construction are concerned.

As shown in Figure 8, the outer frame portion 14 has a flat back wall 26 rigid along the outer longitudinal edge thereof with a flat outer side wall 28, that is disposed normally to said back wall. Along its inner longitudinal edge, the back wall 26 is integral or otherwise made rigid with an inner side wall 30 that is also normal to the back wall. The inner side wall 30, in this connection, is of substantially reduced width as compared to the width of the outer side wall 28.

Integral or otherwise rigid with the forward edge of the outer side wall 28 is an outer, front side wall portion 32 arranged parallel to the back wall 26, said front side wall portion 32 merging into an inclined, intermediate front side wall portion 34, which in turn merges into an inner, front side wall portion 36 extending to the inner side wall 30 and arranged parallel to the portion 32 and the back wall 26.

A longitudinal series of closely spaced, curtain-engaging nails or pins provided upon the outer frame portion 14, and upon each of the other outer frame portions 10, 12, and 16 respectively. The nails 38 are fixedly mounted upon their associated frame portions and extend throughout the length thereof, said nails projecting laterally of the curtain stretcher when said curtain stretcher is erected in the manner shown in Figures 1 and 2, for engaging the edge of a curtain to be stretched, not shown.

Fixedly mounted upon the inner surface of the outer side wall 28 is a longitudinal rib 40, said rib constituting a projection within the outer frame portion 14 and extending, preferably, throughout the length of said outer frame por-

tion. The other outer frame portions 10, 12, and 16 are provided with similar internal projections, as will be readily understood.

That end of the outer frame portion 14 that receives the inner frame portion 22 is formed with a longitudinal slot 42, said slot being provided in the inner front wall portion 36 and opening upon the adjacent end of the frame portion 14.

10 A latch means is provided on each outer frame portion for engaging the inner frame portion associated therewith in selected positions of telescopic adjustment of the frame portions, the construction of said latch means being particularly well shown in Figures 5 and 8. As shown in these figures, the latch means includes a latch member 44 pivotally mounted intermediate its ends upon a pivot pin 46, that is journaled in and extends between pivot brackets 48 fixedly 15 mounted upon the inner side wall 30. One end of the latch member is continuously biased outwardly of the inner side wall 30 by means of a leaf spring 50 that engages said inner side wall, the other end of said latch member being formed 20 with an inturned lip 52 that is continuously forced inwardly, by reason of the pressure of said spring, through an aperture 54 formed in the inner side wall. The lip 52, as shown in Figure 5, will frictionally engage the telescoped 25 part of the inner frame portion 22 in any position to which said inner frame portion is telescopically adjusted relative to the outer frame portion 14, thus to retain the frame portions in selected positions of telescopic adjustment.

30 Considering the construction of the several inner frame portions, a description of the cross-sectional shape and inner construction details of one will suffice for all, and accordingly, the inner frame portion 22 will be the only inner frame portion described.

35 As seen in Figure 8, the inner frame portion 22 is of tubular formation, and is shaped cross-sectionally in a manner similar to the outer frame portion 14 associated therewith, it being understood, however, that the inner frame portion will be slightly smaller in cross-sectional area so as to permit it to fit snugly within and be slidable relative to the outer frame portion 14.

40 The inner frame portion 22 includes an outer front wall portion 56, merging into an inclined, intermediate front wall portion 58, which in turn merges into a flat, inner front wall 60. An inner side wall 62 is disposed normally to and is integral with the portion 60, and has slideable contact with the inner surface of the inner side wall 30 of the frame portion 14.

45 The frame portion 22 also includes a flat back wall 64 that slides upon the back wall 26, said back wall 64 merging into and being normal to an outer side wall 66.

50 The outer side wall 66, intermediate its respective longitudinal edges, is formed, from end to end thereof, with a longitudinal recess 68 receiving the projection 40 of the outer frame portion 14, and formed in the inner wall of said recess 65 is a series of elongated, closely spaced slots 70 (Figure 4).

55 A cam carrier plate 72 is provided, that extends the length of the inner frame portion 22, said plate being housed within said inner frame portion and being fixedly mounted therein in any suitable manner.

60 As seen from Figure 8, the cam carrier plate has a back wall 74 positioned against the inner wall of the recess 68, said back wall 74 being

5

formed with a longitudinal series of elongated slots 76 that are registered with the slots 70.

Mounted upon the plate 72 is a longitudinal series of cams each of which includes an arm 78, one end of which is upwardly offset as at 80 and extended through the registering slots 78, 76 (Figure 4). The arms 78 are pivotally mounted, intermediate their ends, on pivot pins 82 carried by the cam carrier plate 72, and formed on the other ends of said arms are arcuate cam plates 84, the construction of which is particularly well illustrated in Figures 5 and 7.

Each cam plate 84 is formed with an arcuate slot 86, the slots 86 defining cam slots and being arranged obliquely to the axis of pivotal movement of the arms 78.

Formed upon the carrier plate 72, and extending through the full length of said carrier plate, is an upstanding front wall 88, formed from end to end thereof with a longitudinal series of dovetail recesses in which blocks 90 are slidably mounted. The blocks 90, in this connection, are mounted in the front wall of the cam carrier plate for movement between extended positions shown at the left in Figure 7, and retracted positions shown at the right in this figure. The blocks, in this regard, move to their retracted and extended positions along lines parallel to the axes of pivotal movement of the cam arms 78, and carried by each block is a curtain-engaging nail 92. In the extended positions of the blocks 90, the nails 92 carried thereby project through apertures 93 formed in the wall of the inner frame portion 22, said nails being recessed wholly within said frame portion 22 when the frame portion 35 is telescoped within its associated outer frame portion 14.

Each of the blocks 90 is provided with a laterally extended pin 94, extending into the cam slot 86 associated with said block, and thus it will be seen that on pivotal movement of the cam arm 78 in one direction, the blocks 90 will be biased to one position, said blocks being biased to their other position on pivotal movement of the cam arms in an opposite direction.

Normally, the blocks 90 and their associated nails 92 are disposed in an extended position, and to this end, a spring 96 is associated with each cam, said spring being connected at one end to the carrier plate 72 and at its other end to the upwardly offset end 80 of the cam arm 78. The springs 96 are so tensioned, in this connection, as to normally swing the cam arms 78 to positions perpendicular to the longitudinal center line of the frame portion 22, and in this position of the cam arms 78, the blocks 90 will be in their extended positions. When, however, the cam arms 78 are swung in one direction to the position shown at the right in Figure 5, the blocks 90 will be retracted, against the tension of the springs 96.

The movement of the cam arms 78 to the position shown at the right in Figure 5 is effected by engagement of the projection 46 of the frame portion 14 with the ends 80 of the cam arms. Thus, assuming that the frame portion 22 is being telescoped into the frame portion 14, the projection 46 will engage each cam in succession, so as to cause the nails 92 to be retracted successively. During this operation, each nail 92 will move, while still extended, into the slot 42, and before it reaches the inner end of said slot, will be withdrawn into the frame portion 22. Similarly, when the frame portion 22 is withdrawn relative to its associated frame portion 14, each nail 92 will move upwardly into the slot 42, in succession.

6

In this way, a rectangular pattern of curtain-engaging nails is provided in the curtain stretcher at all times, in any position of relative adjustment of the component frame members thereof, with all the nails of said rectangular pattern or series being coplanar to all intents and purposes, thus to effect the retention of the stretched curtain in a flat position and cause the curtain to be stretched uniformly throughout its area.

Considering now the means whereby the several frame members are connected at the corners of the curtain stretcher, a similar connecting means is provided at each corner, and accordingly, one only will be described. As shown in Figure 3, this means includes an angle plate 98 secured fixedly to the outer frame portion 16, a like plate being secured fixedly to the inner frame portion 24, the inner frame portion 22, and the outer frame portion 14.

Pivottally mounted upon one leg of the angle plate 98 is a swinging latch member 100, having a finger grip 102 at its free end and a side recess 104, said recess 104 also being disposed at the free end of said latch member. A slot 106 is formed in the leg of the angle plate on which said latch member is movably mounted, the latch member swinging into position across said slot.

That end of the frame portion 16 on which the angle plate 98 is mounted is formed with indentations 108, 110 that are adapted to receive the adjacent end of the frame portion 18, said frame portion 18 being formed with a latch plate 112 extendable through the slot 106, and formed with a locking recess 114 adapted to receive the notched or recessed end of the latch member 100.

By reason of this arrangement, connecting means is provided which permits the several frame members of the curtain stretcher to be disconnected whenever desired, thus to impart a knock-down characteristic to the entire assembly, whereby the several components of said assembly can be separated from one another and stored in a small area.

In Figures 1 and 2, there is illustrated the means whereby the frame of the curtain stretcher is supported in a substantially vertical plane, said means including a pair of tubular standards 116 spaced longitudinally of the stretcher frame.

Telescopically mounted in the open upper ends of the standards 116 are extension members 118, said extension members 118 having angular support plates 120 fixedly secured to their projecting upper ends, the supports 120 forming ledges adapted to supposedly engage under the frame portions 10, 12.

Fixedly secured to the respective standards 116, and disposed intermediate the opposite ends of said standards, are supporting yokes 122 having vertically spaced, laterally projecting arms that receive between them the frame portion 12, 20 respectively.

The lower end of each supporting yoke 122 is of bifurcated construction, and mounted between the forks of said lower arm of the supporting yoke is a pivoted clamp 124 of inverted, L-shaped formation.

The clamp member 124 is pivotally mounted, as at 126, on depending ears provided upon the lower end of the yoke 122, and secured to said clamp member, at the lower end thereof, is a leaf spring 128, that extends into engagement with the standard 116. Thus, the clamp member 124 is yieldably pressed into engagement with the frame portion associated therewith, to releasably grip the same, the angular plates 120

then being forced into engagement with the frame portions 10, 18 and held in proper position by means of a friction latch 130, formed identically to the latches illustrated in Figures 5 and 8, and mounted upon the standards 116.

Mounted upon each standard 116 is a foldable supporting leg, the standard being provided with ears 132 carrying a pivot pin on which the folding leg 134 is swingably mounted. Each leg 134 is provided with a pivoted latch 136, the lip of which is extendable into any of a plurality of notches provided upon the ears 132, thus to retain the leg 134 in selected positions to which it is swung relative to the standard 116 associated therewith.

From the illustration and description provided herein, it is apparent that the entire assembly can be knocked down, whenever desired, and folded in a small area, the several inner frame portions telescoping fully within the outer frame portions associated therewith. Further, when the curtain stretcher is to be used, the frame thereof can be adjusted readily as to length and width, and the act of making the telescopic adjustments automatically causes the retraction or extension of some of the movable nails 92, so that in any position of adjustment of the parts, a continuous rectangular series of laterally projected, curtain-engaging nails is exposed.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claims.

What is claimed is:

1. A curtain stretcher comprising: a rectangular frame including a pair of parallel longitudinal members and a pair of parallel transverse members connected to and extending between the longitudinal members, each member being formed of telescopically related frame portions; a longitudinal row of nails fixedly mounted on one portion of each member; nails mounted on the other portion of each member for retraction into said other portion; cams operatively associated with the respective nails of said other portion to retract the same; and means on the first-named portion arranged to engage said cams and actuate the same to the nail-retracting position thereof, responsive to telescoping of said other portion into the frame portion associated therewith.

2. A curtain stretcher comprising: a rectangular frame including a pair of parallel longitudinal members and a pair of parallel transverse members connecting to and extending between the longitudinal members, each member being formed of telescopically related frame portions; a longitudinal row of nails fixedly mounted on one portion of each member; nails mounted on the other portion of each member for retraction into said other portion; cams operatively associated with the respective nails of said other portion to retract the same; and means on the first-named portion arranged to engage said cams and actuate the same to the nail-retracting position thereof, responsive to telescoping

of said other portion into the frame portion associated therewith, said means being arranged for engaging each cam in succession, whereby to effect retraction of the second-named nails in succession during continuing telescoping movement of said other portion into said one portion.

3. A curtain stretcher comprising: a rectangular frame including a pair of parallel, longitudinal members and a pair of parallel transverse members connected to and extending between the longitudinal members, each member being formed of telescopically related frame portions; a longitudinal row of nails fixedly mounted on one portion of each member; blocks arranged longitudinally of the other portion of each member and mounted for retraction thereinto; nails carried by the respective blocks; cams operatively associated with the respective blocks to retract the same responsive to movement of the cams in one direction; means on the first-named portion arranged to engage said cams and actuate the same to the block-retracting position thereof responsive to telescoping of said other portion into the frame portion associated therewith, said means being arranged for engaging each cam in succession, whereby to effect retraction of the blocks in succession during continuing telescopic movement of said other portion into said one portion; and springs operatively associated with the respective cams for normally urging the cams in an opposite direction, thus to retain the blocks and nails carried thereby in a normally extended position.

4. A curtain stretcher comprising: a rectangular frame including a pair of parallel longitudinal members and a pair of parallel transverse members connected to and extending between the longitudinal members, each member being formed of telescopically related frame portions; a longitudinal row of nails fixedly mounted on one portion of each member; blocks arranged longitudinally of the other portion of each member and slidably mounted therein for movement transversely of said other portion to retracted and extended positions; nails carried by the respective blocks; cams movably mounted in said other portion and individually engaged with the respective blocks to bias the same to a retracted position responsive to movement of the cams in one direction; means on the first-named portion arranged to engage said cams and actuate the same to the block-retracting position thereof responsive to telescoping of said other portion into the frame portion associated therewith, said means being arranged for engaging each cam in succession, whereby to effect retraction of the blocks in succession during continuing telescoping movement of said other portion into said one portion; and springs operatively associated with the respective cams for normally urging the cams in an opposite direction, thus to retain the blocks and the nails carried thereby in a normally extended position.

5. A curtain stretcher comprising: a rectangular frame including a pair of parallel longitudinal members and a pair of parallel transverse members connected to and extending between the longitudinal members, each member being formed of telescopically related frame portions; a longitudinal row of nails fixedly mounted on one portion of each member; blocks arranged longitudinally of the other portion of each member and slidably mounted therein for movement transversely of said other portion to retracted

and extended positions; nails carried by the respective blocks; cams pivotally mounted intermediate their ends in said other portion and individually engaged at one end with the respective blocks to bias the same to a retracted position responsive to the swinging movement of the cams in one direction; a projection on the first-named portion arranged to engage the other ends of said cams to swing the cams to the block-retracting position thereof responsive to telescoping of said other portion into the frame portion associated therewith, said projection being arranged for engaging each cam in succession, whereby to effect retraction of the blocks in succession during continuing telescoping movement of said other portion into said one portion; and springs connected at opposite ends to the cams and said other portion respectively, for normally swinging the cams in an opposite direction, thus to retain the blocks and the nails carried thereby in a normally extended position.

6. A curtain stretcher comprising: a rectangular frame including a pair of parallel longitudinal members and a pair of parallel transverse members connected to and extending between the longitudinal members, each member being formed of telescopically related frame portions; a longitudinal row of nails fixedly mounted on one portion of each member; blocks arranged longitudinally of the other portion of each member and slidably mounted therein for movement transversely of said other portion to retracted and extended positions; nails carried by the respective blocks; cams pivotally mounted intermediate their ends in said other portion for movement about axes parallel to the line of sliding movement of the blocks, said cams having slots at one end oblique to said axes and the blocks including pins slidably engaged in the slots, for biasing of the blocks to a retracted position responsive to swinging movement of the cams in one direction; a projection on the first-named portion arranged to engage the other ends of said cams to swing the cams to the block-retracting position thereof responsive to telescoping of said other portion into the frame portion associated therewith, said projection being so disposed relative to said other ends of the cams as to engage each cam in succession, whereby to effect retraction of the blocks in succession during continuing telescoping movement of said other portion into said one portion; and springs connected at opposite ends to the cams and said other portion respectively, for normally urging the cams in an opposite direction, thus to retain the blocks and the nails carried thereby in a normally extended position.

7. A knock-down curtain stretcher adjustable as to width and length, comprising: a rectangular frame including a pair of parallel longitudinal members and a pair of parallel transverse members connected to and extending between the longitudinal members; separable, fixed connections between the members at the several corners of the frame, each member being formed of telescopically related frame portions; a longitudinal row of nails fixedly mounted on one portion of each member; blocks arranged longitudinally of the other portion of each member and slidably mounted therein for movement transversely of said other portion to retracted and extended positions; nails carried by the respective blocks; cams pivotally mounted intermediate their ends in said other portion for movement about axes parallel to the line of slid-

ing movement of the blocks, said cams having slots at one end oblique to said axes and the blocks including pins slidably engaged in the slots, for biasing of the blocks to a retracted position responsive to swinging movement of the cams in one direction; a projection on the first-named portion arranged to engage the other ends of said cams to swing the cams to the block-retracting position thereof responsive to telescoping of said other portion into the frame portion associated therewith, said projection being so disposed relative to said other ends of the cams as to engage each cam in succession, whereby to effect retraction of the blocks in succession during continuing telescoping movement of said other portion into said one portion; and springs connected at opposite ends to the cams and in said other portion respectively, for normally urging the cams in an opposite direction, thus to retain the blocks and the nails carried thereby in a normally extended position.

8. A knock-down curtain stretcher adjustable as to width and length, comprising: a rectangular frame including a pair of parallel longitudinal members and a pair of parallel transverse members connected to and extending between the longitudinal members; separable, fixed connections between the members at the several corners of the frame, each member being formed of tubular, telescopically related frame portions; a longitudinal row of nails fixedly mounted on and disposed exteriorly of one portion of each member; blocks arranged longitudinally of the other portion of each member and slidably held therein for movement transversely of said other portion to retracted and extended positions; nails carried by the respective blocks, said last-named nails being disposed exteriorly of their associated portions in the extended positions of the blocks and interiorly of said associated portions in the retracted positions of the blocks; cams pivotally mounted intermediate their ends within said other portion for movement about axes parallel to the line of sliding movement of the blocks, said cams having slots at one end oblique to said axes and the blocks including pins slidably engaged in the slots, for biasing of the blocks to a retracted position responsive to swinging movement of the cams in one direction; a projection within the first-named portion arranged to engage the other ends of said cams to swing the cams to the block-retracting position thereof responsive to telescoping of said other portion into the frame portion associated therewith, said projection being so disposed relative to said other ends of the cams as to engage each cam in succession, whereby to effect retraction of the blocks in succession during continuing telescoping movement of said other portion into said one portion; and springs connected at opposite ends to the cams and said other portion respectively, for normally swinging the cams in an opposite direction, thus to retain the blocks and the nails carried thereby in a normally extended position.

WALTER KARAS.
